(57) **CLAIM**

The ornamental design for a uterine manipulator, as shown and described.

DESCRIPTION

FIG. 1 is a top left side perspective view of a uterine manipulator in accordance with the new design;

FIG. 2 is a left side isometric view thereof;

FIG. 3 is a right side isometric view thereof;

FIG. 4 is a top isometric view thereof;

FIG. 5 is a bottom isometric view thereof;

FIG. 6 is an enlarged front left side isometric view thereof; and,

FIG. 7 is an enlarged left side isometric view thereof.

The broken lines immediately adjacent the shaded areas in FIGS. 1 and 5-7 represent the bounds of the claimed design, with the lines themselves and the areas within them forming no part of the claimed design.

1 Claim, 4 Drawing Sheets
